UNITED STATES PATENT OFFICE.

KENNETH E. BREWER, OF CHICAGO, ILLINOIS, ASSIGNOR TO CHAS. A. BREWER & SONS, A FIRM COMPOSED OF CHARLES A. BREWER, NELSON C. BREWER, KENNETH E. BREWER, AND EVERETT R. BREWER, OF CHICAGO, ILLINOIS.

GAME COUNTER.

Application filed October 22, 1925. Serial No. 64,090.

This invention relates to improvements in game counters or boards, and has reference more particularly to that type wherein one or more balls are confined within a hollow structure the bottom of which is formed with cavities or pockets into which the balls, the device having been shaken, come to rest; the cavities or rows of cavities having different value or character designations identified by indicia located opposite the same which determine the values or characters of each throw. In its principal contemplated use the device is intended to take the place of the ordinary dice shaker and dice used as an auxiliary in such games as backgammon to determine the extent of progressive movements toward a goal. It may also be used as a bagatelle board or the like, constituting in itself a complete game device of the chance variety.

One simple practical embodiment of the invention is illustrated in the accompanying drawing, in which—

Fig. 1 is a top plan view;

Fig. 2 is a transverse section, on an enlarged scale, taken on the line 2—2 of Fig. 1; and

Fig. 3 is a similar cross-section in the vertical plane of one of the fastening devices on the line 3—3 of Fig. 1.

Referring to the drawing, 5 designates a bottom plate preferably a sheet of cardboard or the like, on which is placed a somewhat thicker plate 6 that constitutes a false bottom and is formed with a large number of round holes or ball pockets 7, these latter being preferably grouped in longitudinal and transverse rows, as clearly shown in Fig. 1. Superposed upon the false bottom 6 is a still thicker plate 8 of wood, heavy cardboard, or any other suitable material, which plate is formed with a central oblong opening 9, the side and end walls of which determine the lateral boundaries of the chamber within which the round balls or dice are free to move when the board is tilted or shaken. Pasted on the upper surface of the intermediate plate 8 is a sheet of paper 10 in which is formed an oblong opening registering with the opening 9. The upper surface of the sheet 10 is ruled crosswise to form on each side of the central chamber 9 parallel spaces 11 which lie opposite the ends of the transverse rows of

holes 7; and in these spaces are printed value or character designating indicia, such as the duplicate groups of numerals shown in Fig. 1. These indicia are preferably so grouped as to be of minimum value at the ends of the playing field and of progressively increasing value from the ends to the middle; the object of this arrangement being to prevent any advantage to the player from tilting the board endwise to thereby cause the counters to roll toward the lower end when making a play. It will be observed that the two rows of numerals on opposite sides of the central chamber respectively are relatively inverted so as to be easily readable whichever end of the board is uppermost. Within the chamber or playing field 9 are a plurality of counters or dice taking the form of round balls 12 of a size to just seat in any of the pockets 7. Overlying the paper sheet 10 is a sheet of isinglass or other transparent substance designated by 13, and permanently enclosing and sealing the side and end margins of the assembled structure are U-shaped binding strips 14 preferably of cloth or tape; the complete assembly being securely united by wire staples 15.

In the preferred manner of using the device, the players turn the shaker bottom side up, shake it edgewise a few times, and then drop it face side up on the table. The player having the highest sum total, as shown by the numbers opposite the rows in which the balls lodge, becomes player No. 1, etc. In figuring the shaker counts, a player may use the number designated by each ball, or the sum total of the numbers designated by all the balls. When two, three or more balls lodge in the same transverse row, the player may double, triple, etc. the number designating that row.

Various modifications and refinements may be added to the simple form of the invention illustrated, if desired, to widen the scope of the device and heighten the playing interest; as, for example, certain holes or rows of holes may be colored differently, and the balls may be correspondingly colored, with a double or otherwise increased value on any ball coming to rest in a hole or row of its own color. Again, in using the device with games wherein different colors indicating progressive steps or

stages in the playing of the game are employed, colors may be used in lieu of the numerals shown to indicate such steps or stages determined by the throws.

5 The device constructed substantially as shown and described can be simply and cheaply made in a size such that it may conveniently be carried in a vest pocket, and hence constitutes a handy and convenient 10 game counter or shaker less bulky and more convenient to carry about than the ordinary dice box and dice. While I have shown the board equipped with a pair of balls or counters, it is manifest that any number from 15 one up may be employed, as desired.

I claim—

1. A game counter of the character described, comprising a flat rectangular permanently closed box formed with a central 20 elongated narrow sealed chamber having a transparent top wall, and a flat bottom wall formed with ball pockets grouped in longitudinal and transverse rows relatively to said chamber, one or more balls in said chamber, and duplicate groups of play value indicating numerals located one on each side of said chamber opposite the respective transverse rows of ball pockets, said numerals being progressively arranged from lowest 30 to highest from the ends to the center of said chamber, and all the numerals on the two sides being relatively inverted to facilitate reading of the same with either end of the box uppermost.

2. A game counter of the character described, 35 comprising a rectangular bottom plate, a false bottom overlying said bottom plate and formed with transverse rows of ball pockets, a relatively thick plate superposed on said false bottom and formed with a central elongated opening defining the lateral boundaries of the playing chamber, balls in said chamber, play value identifying characters on the longitudinal sides of the upper surface of said thick plate located 40 opposite the respective rows of pockets, a transparent plate overlying said thick plate, and means for uniting said plates at their margins.

3. A game counter of the character described, 45 comprising a rectangular bottom plate, a false bottom overlying said bottom plate and formed with transverse rows of ball pockets, a relatively thick plate superposed on said false bottom and formed with 50 a central elongated opening defining the lateral boundaries of the playing chamber, balls in said chamber, play value identifying characters on the longitudinal sides of the upper surface of said thick plate located 55 opposite the respective rows of pockets, a transparent plate overlying said thick plate, a flexible binding strip covering the marginal portions of said plates, and wire staples 60 passed through and uniting said binding strip and marginal portions.

KENNETH E. BREWER.
